ATTORNEY

UNITED STATES PATENT OFFICE

FREDERICK B. HUFFMAN, OF SPOKANE, WASHINGTON

SLIDE SCALE

Application filed October 7, 1930. Serial No. 486,991.

My present invention relates to an improved slide scale for use in combination with a T-square, as employed by draftsmen, engineers, and others. The primary object of the invention is the provision of an adjustable measuring instrument combined for use with the blade of the T-square in such manner that plans may be pointed or plotted; measurements for dimensions may readily be made; and both perpendicular and horizontal lines be accurately drawn, the perpendicular lines being drawn by the use of a triangle. A protractor or other geometrical instrument may also be used in combination with T-square and slide scale, as will be apparent to anyone skilled in the use of such instruments.

In carrying out my invention the instrument may be used as a combined device, the T-square may be used for the performance of the functions of the usual or customary T-square, and the slide scale may be utilized for solving problems where the customary slide scale is needed.

The invention consists essentially in the combination with the blade of the T-square, of an adjustable slide scale and a complementary fixed scale, and in other combinations and arrangements of parts related thereto, as will hereinafter be more fully set forth and claimed.

In the accompanying drawing I have illustrated one complete example of the physical embodiment of the invention wherein the parts are combined and arranged according to the best mode I have thus far devised for the practical application of the principles of my invention.

Figure 1 is a plan view of a T-square, partly broken away for convenience of illustration and showing the physical embodiment of my invention.

Figure 2 is an enlarged transverse sectional view at line 2-2 of Figure 1.

Figure 3 is an enlarged plan view of a portion of the instrument, showing by dotted lines the manner of releasing the removable slide scale from the T-square, and for applying the slide scale to the blade of the T-square.

Figure 4 is a view at the back edge of the instrument, as at line 4-4 of Figure 1.

In the physical embodiment of my invention as illustrated in Figure 1 I employ the well known draftsman's T-square having the head 1 and blade 2, with the front ruling edge 3 and back edge 4, all of which are fashioned of suitable material, and the T-square is adapted for the customary uses of such an instrument.

In converting the T-square for use in carrying out my invention I utilize a guide block 5 of hard wood, metal, or other appropriate material, and this block is fastened in a mortise 6 in the blade, a dovetail edge 7 being provided on the block for insuring a rigid and stable arrangement of the block, and the latter is fastened, as by gluing (or in other suitable manner) in position. The dovetailed bottom edge of the block is flush with the bottom of the blade, but the upper or top edge of the block projects above the upper face of the blade, and as shown, the block extends longitudinally of the blade and parallel with the front ruling edge 3 of the blade.

Adjacent to the back edge of the blade a scale plate 8 is fastened to the blade by rivets, screws, or other fastening devices as 9, and this plate or strip has a front guide edge 9', parallel with the front ruling edge 3 of the blade, and of course parallel with the guide block 5.

The plate or strip 8, through the use of its guide edge 9', guides the movement of a slide plate 10, in combination with the guide block 5. At the guide edge 9' of the fixed plate and along the back edge of the slide plate a vernier scale 11 is arranged for measuring fraction parts, and this vernier scale is adapted for use with a linear scale (twelve inches) laid out on the front edge of the slide plate 10.

The front or working edge of the adjustable, slidable scale plate coincides, approximately, with the front or ruling edge of the blade, and this inch-scale may be used for laying out dimensions and plotting plans, by means of a triangle, protractor, or other

instrument adapted for use with the straight edge or ruling edge of the blade.

The slide plate 10 is fashioned with a longitudinal slot 12, terminating near the ends of the plate, and the slot fits over the guide block 5 in such manner as to insure a neat and close fit between the slide plate, its guide block and the guide plate 8. In its upper face the slide plate may be provided with depressions as 13 to receive the point of a pencil, as a hard drawing pencil, and by means of the pencil a close adjustment of the slide plate and scale may be secured.

The slide plate is held down in proper position on the blade by means of a pair of spaced, spring fingers 14 mounted on the ends of the block, and with their opposite ends bearing on the slide plate with sufficient tension as to hold the plate to the blade, but at the same time permit sliding of the plate.

These resilient blades or spring fingers are mounted in longitudinally extending slots or slits 15 opening at the opposite ends of the guide block, and rivets or pins as 16 secure the blades in their slots and at the same time act as pivots for the blades. The slits or slots are of sufficient length to permit the blades to be swung on their pivots with their long axes parallel with the length of the block, as indicated in Figure 3, and when so turned or swung, the slide plate is free to be removed from the blade.

For clamping the slide plate in adjusted position after it has been properly adjusted for the desired scale or measurements I use a pair of resilient clamps 17 or spring blades that are larger and possess greater tension than the spring fingers, and these clamps, at the free ends bear on the top face of the slide plate.

The clamps or resilient blades are mounted on the fixed guide-plate, and for this purpose the latter has near its ends upwardly projecting studs or screws 18 over which the perforated ends of the clamps are fitted, and clamp nuts 19 on the screws bear against the clamp blades and press them with varying degrees of tension against the slide plate to hold the latter in adjusted position while the instrument is being utilized.

From this description taken in connection with my drawing it will be apparent that I have provided an instrument that is comparatively inexpensive in cost of production and manufacture, but which may be used with facility, accuracy, and precision as a labor saving device for the draftsman, engineer, and others accustomed to using such instruments.

Having thus fully described my invention, what I claim as new and desire to secure by Letters Patent is:—

1. The combination with the blade of a T-square and a guide block rigid therewith, of a slotted plate having a scale edge coinciding

with the ruling edge of the blade, resilient means mounted on the block for pressing the plate against the blade, a guide plate back of the slide plate and a vernier scale on adjoining edges of the slide plate and guide plate, and means on the guide plate for frictionally engaging the slide plate to retain the latter in adjusted position. 70

2. The combination with a straight edge blade and a guide block rigid therewith, and a fixed guide plate on the blade, of a slotted slide plate co-acting with the guide block and said fixed plate, said guide plate and slide plate having a vernier scale on adjoining edges, resilient means on the block for retaining the slide plate against the blade, and means on the guide plate for frictional engagement with the slide plate for retaining the latter in adjusted position. 75 80

3. The combination with a blade of a T-square, a slotted guide block rigid therewith, and a guide plate rigid with the blade and spaced from the block, of a slotted slide plate embracing the block and a vernier scale on adjoining edges of the guide plate and slide plate, pivotal resilient blades mounted in the slotted guide block for engaging said slide plate, and spring clamp blades mounted on the guide plate for frictionally engaging the slide plate. 95

In testimony whereof I affix my signature.
FREDERICK B. HUFFMAN.
